Inventor;
EDWIN AUGUST MILLER

George L. Terry Esq.
By Attorney.

Filed August 1, 1947. Patented Sept. 18, 1951. Serial No. 778,443. This application is a continuation-in-part of my application Serial No. 778,443, filed August 1, 1947, now abandoned.

My invention relates to a switch blade, a mechanical part of an electric switch, and more particularly to a switch blade having a relatively sliding rigid link extension of the compression arm.

UNITED STATES PATENT OFFICE

2,568,652

SWITCH BLADE

Edwin August Miller, Fairfield, Conn.

Application October 7, 1947, Serial No. 778,443

3 Claims. (Cl. 200—67)

1

This invention relates to a switch blade, a mechanical part of an electric switch, and more particularly to a switch blade having a relatively sliding rigid link extension of the compression arm.

The object of the invention is to provide a compression arm with extension of a novel character providing a sliding movement of such arm.

With reference to the accompanying drawing, the Figure 1 is a plan view of the device; Figure 2 is a side view of the device with parts in normal at-rest position; Figure 3 is a plan view of the device omitting the coil spring; Figure 4 is a perspective view of a detail of the device; and Figure 5 is a cross-section of the previous detail.

With more particular reference to the accompany drawing, the numeral 1 designates the body of the switch blade of sheet metal. The body 1 is provided with an elongated opening 2 therethrough within which is the compression arm 3 integral with the body 1 at one end of said opening 2. The body 1 of cantilever type is secured at one end 1A to a base (not illustrated) by means of rivet 18. The arm 3 may be slightly bent upwardly, as at 4, for a normal over-centered position with respect to the plane of the body 1, as illustrated by the Figure 2. At the other end of the opening 2 the body 1 is provided with a rigid projection 5 slightly extending into, and within the plane of, said opening 2.

The compression arm 3 at its extremity 6 is provided with a reduced portion 7 providing the side shoulders 8. A rigid link 9 is provided with the opening 9A, through one end of which depends the hook member 9B. Downwardly bent-end portions 10 of the link 9 are substantially at right angles thereto of which one bent-end portion is provided exteriorly with a cupped groove 11, and the other bent-end portion 10 is provided with a slot 12 therethrough, the groove 11 being adapted to receive therein the rigid body projection 5, and the compression arm 3 being insertible within the slot 12 of the other bent-end portion 10 for a free sliding movement therein, the link 9 normally being tipped upwardly and adapted for a tilting movement within the body opening 2 upon its hinged connection with the projection 5.

A coil spring 13 is positioned around the reduced portion 7 of the compression arm 3 with one end of the spring 13 engaging the side shoulders 8, and the opposite end engaged over the hook 9B, said spring 13 thus being positioned for movement wholly within the link 9 and permit-

ting a spring-pressed sliding movement of the reduced portion 7 within the slot 12.

The form of switch blade illustrated by the Figures 1 and 2 is provided with upper and lower contacts 14 and 15 at the free end 6 thereof for pendulous movement between the fixed stops 19 and 20.

In use, assuming that the movable parts of the device are relatively positioned as illustrated by the Figure 2, manual or other pressure may be applied to the push element 17 sufficiently to move through the opening 2 of the body 1 the hinged link-extended extremity 6 of the arm 3. The said opening 2 is of lesser length than the length of the link 9 and arm 3 in normal position with link out of alignment therewith. The arm 3 becomes flexed as its extremity 6 is forced to slide within the slot 12 and compresses the spring 13 engaged with the side shoulders 8 while the link 9 is pivotally moved, upon the projection 5, into alignment with the arm 3 until the extremity 6 of the arm 3 passes a centered position with respect to the body 1. The centered position of the extremity 6 of the arm 3 so distorts the body 1 that, upon the sudden release of the extended arm 3 from its centered position, the pendulous end of the body 1 is moved with a snap-action between fixed stops 20 and 19 thereby breaking contact 15 with the stop 20 and contacting contact 14 with the stop 19 as the extended arm 3 passes from its said centered position to an off-centered position at the opposite side of the body 1.

While the spring 13, illustrated by the Figures 1 and 2, it is understood that any other form of spring may be employed, within the scope of the invention, to get a desired operation required by a particular equivalent form of structure of device; for springs of varied forms provide a wide choice of associated link actions. The relative action, as between the tilted link 9 and the sliding compression arm extremity 6, being more or less independent of one another in that each has a distinct function which, as combined, permits a variance in the length of either, the link 9 or the spring 13, for a more gradual operating pressure and quicker contact snap-action.

If a maintained type of operation is desired in said device, the push element 17 may include means (not illustrated) for operation, manual or otherwise, at both ends thereof. In such a case, the slight bend 4 in the compression arm 3 would be omitted.

I claim:

55 1. A switch blade means for an electric switch,

said means comprising a sheet-metal body having an elongated opening therethrough, upper and lower contacts carried by said body upon opposite surfaces thereof and movable therewith between fixed stops, a rigid projection provided by said body and extending into one end of said opening, a compression arm carried by said body and extending into said opening from the opposite end thereof, said arm having a reduced extremity providing shoulders thereon, a tilttable rigid link having bent end portions, a cupped groove exteriorly provided in one of said bent end portions for a hinged engagement therein with said rigid projection, a slot provided through the other bent end portion for a sliding engagement therein of a portion of said compression arm, spring means carried by said reduced extremity of the compression arm, the opposite end of said means engaged by a part of said link, and an actuating member engageable with a surface of the compression arm for moving said arm, and the connected link, through said opening, past center and to an off-centering position with respect to said blade which is thereby distorted with consequent snap-acting movement from one to another of said fixed stops.

2. A switch blade means for an electric switch, said means comprising a sheet-metal body having an elongated opening therethrough, upper and lower contacts carried by said body, each upon opposite surfaces thereof and movable therewith between fixed stops, a rigid projection provided by said body and extending into one end of said opening, a compression arm carried by said body and extending into said opening from the opposite end thereof, said arm having a reduced extremity providing shoulders, a tilttable rigid link having bent end portions and an intermediate depending portion, a cupped groove exteriorly provided in one of said bent end portions for a hinged engagement therein of said rigid projection, a slot provided through the other bent end portion for a sliding engagement therein of the reduced portion of said compression arm, spring means carried within said link and engaging one end

5 of said means with the shoulders of the reduced extremity of said arm, and at the other end engaging the said depending portion of said link, and an actuator for moving said arm and link through said opening, past center and to an off-centering position with respect to said blade which is thereby distorted with consequent snap-acting movement from one to another of said fixed stops.

10 3. A switch blade means for an electric switch, the blade comprising a sheet-metal body having an elongated opening therethrough, upper and lower contacts carried by said body, each upon opposite surfaces thereof and movable therewith between fixed stops, a rigid projection provided by said body and extending into one end of said opening, a compression arm carried by said body and extending into said opening from the opposite end thereof, said arm having a reduced extremity providing shoulders, a tilttable rigid link having bent end portions, one of which has a hinged connection with said rigid projection, a slot provided through the other bent end portion for a sliding engagement therein of a portion of said compression arm, spring means carried within said link and engaging one end with the shoulders of the reduced portion of said arm, and at the other end engaging a portion of said link, and an actuator for moving said arm and link through said opening, past center and to an off-centering position with respect to said blade which is thereby distorted with consequent snap-acting movement from one to another of said fixed stops.
